UNITED STATES PATENT OFFICE.

ANTON T. ANDERSON, OF CHICAGO, ILLINOIS.

WRENCH.

1,309,311.

Specification of Letters Patent. Patented July 8, 1919.

Application filed October 20, 1916. Serial No. 126,795.

To all whom it may concern:

Be it known that I, ANTON T. ANDERSON, a citizen of the United States, residing at 3222 Carroll Ave., Chicago, in the county of Cook and State of Illinois, have invented new and useful Improvements in Wrenches, of which the following is a full, clear, concise, and exact description, reference being had to the accompanying drawing, forming 10 a part of this specification.

My invention relates to wrenches.

One of the objects of my invention is to provide an improved wrench in which the jaw mechanism is pivotally secured to the handle and in which improved means are provided for holding the jaw mechanism in an adjusted position which is simple in construction, easy to manufacture, and efficient and durable in use and in which the adjusting mechanism is easily accessible for operation.

In the drawings in which one embodiment of my invention is shown:

Figure 1 is a side view of a wrench embodying my invention.

Fig. 2 is a view of the other side of the wrench.

Fig. 3 is an edge view of the head of the wrench.

Fig. 4 is a face view of the head of the wrench with the retaining plates removed.

Fig. 5 is a sectional view on the line 5—5 of Fig. 3 showing both dogs in engagement.

Fig. 6 is a sectional view on the line 5—5 of Fig. 3, showing only one dog in engagement.

Fig. 7 is a perspective view of the wedge member.

Fig. 8 is a perspective view of one of the dogs.

Referring to the drawings in detail, the wrench shown comprises a handle 10, jaw mechanism 11 pivotally mounted on the handle 10 and the retaining mechanism 12 for holding the jaw mechanism in adjusted 45 position.

The handle 10 comprises the handle proper 13, an arm 14 extending from the handle 13, to which the jaw mechanism 11 is pivoted, and a guiding and supporting portion 15 for engaging the jaw mechanism 11 to assist in holding it in position. The jaw mechanism 11 comprises a jaw member 16, secured to the arm 14 by means of a pivot 50 pin 17 and a sliding jaw member 18, having 55

a groove 19 for engagement with the rib or guide 20 on the jaw member 16. For adjusting the sliding jaw member 18, a screw 21 is located in the recess 22 in the jaw member 16. This screw 21 is provided with pintles 60 or trunnions 23 located in bearing recesses 24 in the jaw member 16. A part of this screw engages with teeth 25 on the sliding jaw member 18. For holding the sliding jaw member in place and for holding the 65 screw 21 in the recess, the retaining plate 26 is secured to the jaw member 16 by means of screws 27. This plate 26 has an opening through which access may be had to the adjusting screw 21. The retaining mechanism 12 comprises two dogs 29 and 29^a for engagement with a series of teeth 30 on the jaw member 16, a wedge member 31 slidably mounted on the handle 10 and provided with oppositely inclined wedge flanges, 32, 32^a 70 for engagement with the recess 33 in the dog 29, and a leaf spring 34 and a screw 35 for holding the dogs, 29, 29^a and the wedge member 31 in position. The screw 35 extends through an opening 36 in the spring 80 34 and through a slot 37 in the wedge 31. The dogs 29 and 29^a are provided with notches 38 for engagement with the screw 35 whereby the dogs 29 and 29^a are prevented from slipping, with respect to the 85 wedge member 31. In use if it is desired to rotate the jaw mechanism about the pivot 17 in a clockwise direction, (Fig. 1) the upper dog 29 must be thrown to the position shown in Fig. 6. To accomplish 90 this the wedge member 31 is pushed toward the pivot 17, the wedge flange 32^a lifting the dog 29^a out of the engagement with the teeth 30, the dogs 29 and 29^a being held from movement along with the wedge 95 flanges by the engagement of the notches 38 with the screw 35. The jaw mechanism may then be rotated in a clockwise direction, the dog 29^a being lifted clear of the teeth and the dog 29 sliding over them. Similarly by 100 movement of the sliding wedge 31 in the opposite direction, the dog 29 is lifted and the jaw mechanism can be rotated in a contra-clockwise direction. When the jaw mechanism has been adjusted to the desired 105 position, it may be held there by moving the wedge member 31 to mid position, which will move the dogs 29 and 29^a to the position shown in Fig. 5 in which both are in engagement with the teeth 30. The adjustment 110

of the sliding jaw 18 is effected by rotation of the screw 21, which acts on the teeth 25 to move the jaw 18 in or out.

The guiding and supporting portion 15 does not extend far enough over the face of the jaw mechanism to prevent access to the screw 21 in any position of the jaw mechanism. Both jaw members 16 and 18 are so shaped that they may be readily dropped forged.

The plate 26 may be of punched sheet metal. That portion of the handle 13, adjacent the teeth 30 engages and supports the dogs 29 and 29^a when the wrench is in use. This support, adjacent the points of the dogs, lessens the danger of the dogs being broken by the strain put on them.

Having described my invention, what I claim as new and desire to secure by Letters 20 Patent, is:—

1. A wrench comprising a handle, a flat jaw member pivotally secured thereto, said jaw member being provided with a series of ratchet teeth on one face thereof and two 25 oppositely acting dogs supported by said handle for engaging said teeth, and a wedge member having two oppositely inclined wedge surfaces acting on said dogs respectively for moving them into and out of opposite positions with respect to said teeth.

2. A wrench comprising a handle, a flat jaw member pivotally secured thereto, said jaw member being provided with a series of ratchet teeth on one face thereof and two 35 oppositely acting dogs supported by said handle for engaging said teeth, and a wedge member having two oppositely inclined wedge flanges acting on said dogs respectively for moving them into and out of opposite positions with respect to said teeth, each dog having a groove to receive one of said flanges.

3. A wrench comprising a handle, a flat jaw member pivotally secured thereto, said

jaw member being provided with a series of 45 ratchet teeth on one face thereof and two oppositely acting dogs supported by said handle for engaging said teeth, and a wedge member having two oppositely inclined wedge flanges acting on said dogs respectively for moving them into and out of operative positions with respect to said teeth, each dog having a groove to receive one of said flanges, said wedge member having a slot therethrough, a leaf spring bearing on 55 said dogs and having an opening therethrough and a fastening member for said leaf spring extending through said opening and slot and secured to said handle.

4. A wrench comprising a handle member, 60 a flat jaw mechanism pivotally supported thereby, said jaw mechanism comprising an arcuate portion concentric with said pivot, provided with a series of ratchet teeth on one face thereof and a dog supported by said 65 handle for engaging said teeth, said jaw mechanism comprising two jaw members and comprising also a rotatable member supported by said jaw mechanism for effecting the relative adjustment of said jaws, said 70 mechanism being recessed to receive said rotatable member, said handle having an arm adjacent one face of said jaw mechanism to which the jaw mechanism is pivoted and having also a guiding and supporting portion 75 adjacent the periphery of said arcuate portion and engaging the face of said flat jaw mechanism on the side opposite said arm, said recess having an opening between the axis of said jaw mechanism and said arcuate 80 portion through which said rotatable member is accessible, said guide portion not extending far enough to prevent access to said rotatable member through said opening.

In witness whereof, I have hereunto subscribed my name.

ANTON T. ANDERSON.
